ABSTRACT OF THE DISCLOSURE

A faller for a textile machine having a central portion of substantially uniform depth terminating at each end in a head portion of greater depth and in which the pins are supported in a body of rubber located in a longitudinal slot passing through the depth of the faller and extending beyond the ends of the portion of uniform depth and into the head portions, the extension at each end having a smaller average width than the remainder of the slot.

This invention relates to a faller for textile machines of the kind described in Patent No. 3,057,021 that is to say in which the pins are carried by a layer of rubber or other relatively soft material located in a slot between side members. The central portion of such fallers is of substantially uniform depth and terminates at each end in a head portion which is of greater depth so as to cooperate with the driving mechanism of the machine in which the fallers are used. During operation fallers are subjected to varying mechanical stresses largely occasioned by the transfer from one slide to the other. In addition the drag of the fibres being processed on the pins of the faller produces a considerable bending or bowing action at right angles to the axis of the pins. These different types of stresses lead to fatigue in the fallers and it is found that the effects of the fatigue are most marked in the region of the end of the slot between the side members which contains the resilient mounting for the pins. Fallers constructed in the way described above are particularly resistant to such fatigue stresses but with the ever-increasing demands of modern production conditions particularly the very high speeds demanded and also the ability of a machine to run for long periods without the need for any replacement, even the small number of failures resulting from such construction lead to the desire for improvement.

According to the present invention the slot holding the rubber-like material in which the pins are supported extends beyond the ends of the portion of uniform depth and thus terminates in a greater depth of bar. This extension of the slot at each end serves to transfer the concentration of fatigue stresses to a greater depth of metal so that the bar is better able to withstand such stresses. It is found that this modification of the construction results in a significant reduction in the number of failures of fallers under any given operating conditions.

Preferably the extension at each end of the slot has a smaller average width than the remainder. Thus the extension may be parallel-sided and of smaller width than the remainder of the slot or alternatively the extension may taper gradually from the full width of the remainder of the slot. In this way the change of section of the bar is effected in stages thus leading to a greater dispersion of the fatigue stresses. As previously described these fatigue stresses are caused at least in part by bowing of the faller due to the drag of the fibres being processed. This bowing can be reduced by an increase in the stiff-

2

ness of the bar and for this purpose at least one of the side members is made thicker over the region of its mid-height. For purposes of symmetry and ease of manufacture this thickening may take the form of a longitudinal stiffening rib along the inner side of each side member.

The side members are preferably integral with the head portions at each end and this may be achieved either by milling the central slot from a solid bar or by means of a precision casting operation. Alternatively, however, the side members may be secured to the head portions as described in Patent No. 3,057,021.

Machining of the central slot lends itself particularly well to a construction in which the extension of the slot at each end is of reduced width and parallel sided and in which each side member is formed with a longitudinal stiffening rib. For this purpose the solid bar may be machined both from above and below to form first slots each of depth slightly less than half that of the bar so that a layer of material is left between them. This residual central portion of the bar is then machined to form a second slot of lesser width than the first slots and extending beyond their ends. The parts of the central portion which are left after this final machining operation constitute the stiffening ribs and the end portions of the narrower slot constitute the extensions of the main slot.

Constructions in accordance with the invention will now be described by way of example with reference to the accompanying drawings in which:

FIGURE 1 is an elevation partly in section;

FIGURE 2 is a plan view corresponding to FIGURE 1 but shown in section along the line II—II in FIGURE 1;

FIGURE 3 is a sectional end view seen along the line III—III in FIGURE 1;

FIGURE 4 is an elevation of the end portion of an alternative construction; and,

FIGURE 5 is a sectional end view seen on the line V—V in FIGURE 4.

Turning first to FIGURE 1 the faller illustrated comprises a central portion 1 of uniform depth terminating at each end in a head portion 2. Each head portion has a groove 3 for cooperation with guides on the machine in which it is to be used and inclined end portions 4 for engagement with the screw feed mechanism. As can be seen from the drawing the head portions 2 are considerably deeper than the central portion 1. The central portion 1 is formed with a longitudinal slot indicated generally as 6 and which as best seen from FIGURE 3 comprises upper and lower portions 7 and 8 respectively which are both broader than a central portion 9. The broader portions 7 and 8 both terminate at points shown as 10 approximately level with the end of the central portion 1. The narrower slot 9, however, extends beyond this to a point shown as 11 so as to terminate in a depth of faller which is greater than that of the central portion 1. The termination of the slot in this portion of increased depth has the effect already described of transferring the concentration of fatigue stresses to this point, and the fact that the extension of the slot past the point 10 is narrower than the main body of the slot means that the change of section is accomplished in two stages, thus leading to further dispersion of the fatigue stresses.

The pins shown in dotted lines as 15 are held by a body of rubber or similar rubber-like material which occupies the whole of the slot 6, being covered by a metal strip 20, and which is omitted from the drawing for simplicity. The effect of this mounting however, is the same as described in Patent No. 3,057,021 in that although it provides ample support for the pins during operation it nevertheless enables them to be replaced without difficulty when required.

The faller illustrated in FIGURES 1 to 3 is most conveniently produced by milling the slot 6 from a solid bar. For this purpose the slots 7 and 8 are first milled from above and below respectively to leave a residual central portion in the region of the slot 9. These two slots are extended at the ends as far as the points 10 already referred to. A narrower cutter is then used to mill the slot 9 through the residual central portion and this slot is extended at the ends to the points 11 as already described.

The fact that the central slot 9 is narrower than the slots 7 and 8 means that longitudinal stiffening ribs 16 and 17 are left on the inner faces of the two side members 18 and 19 defined by the central slot 6. The effect of these two ribs is to stiffen the assembly as a whole and thus to reduce bowing of the faller which in itself is a major factor leading to fatigue. The main body of rubber holding the pins 15 in position is located in the slots 7 and 8 but these two portions are connected together by a thinner body of rubber passing through the slot 9 and this slot must therefore be sufficiently wider than the pins 15 to allow the rubber to be continuous and thus to exert an adequate grip on the pins 15.

FIGURES 4 and 5 illustrate an alternative form of construction, the nature of which is best seen from the sectional view of FIGURE 5. Once again the central slot 6 is milled from a solid bar, but in this case a tapered milling cutter as shown in dotted lines at 22 is used in place of the parallel-sided cutter used for the slots 7 and 8. Upper and lower slots 23 and 24 are milled by means of this cutter and are extended sufficiently far to meet at the centre. These slots, therefore, taper towards the centre of the bar so that each of the side members 18 and 19 is thicker at its mid height as indicated as 25 and 26. This thickening has an effect equivalent to that of the stiffening ribs 16 and 17 in reducing bowing of the faller.

In addition the ends of the slots 23 and 24, which are shown in FIGURE 4 as 28 and 29 respectively, taper from the full width of slot at a point 30, which is approximately level with the end of the central portion 1, to a narrower width as determined by the shape of the cutter 22. In other words the extension of the central slot 6 is tapered so that the change of section at this point occurs gradually and thus therefore assists the distribution of the fatigue stresses. Owing to the fact that the milling cutter does not pass right through the bar

but merely machines the slots 23 and 24 from above and below respectively, as indicated by the dotted circular arcs 23' and 24' in FIGURE 4, an approximately triangular portion 32 is left at each end of the slot and must be removed by a subsequent operation e.g. by broaching.

I claim:

1. A faller for a textile machine, said faller comprising a body having a central portion of substantially uniform depth terminating at each end in a head portion of greater depth, said body being formed with a longitudinal slot passing through the depth of said body and extending beyond the ends of said portion of substantially uniform depth and into the head portions, a mounting of rubber-like elastomer secured in said slot and a plurality of pins extending through and supported by said mounting.
- 10 2. A faller according to claim 1, in which the extension at each end of said slot has a smaller average width than the remainder.
- 15 3. A faller according to claim 1, in which the extension at each end of said slot is parallel-sided and is narrower than the remainder.
- 20 4. A faller according to claim 1, in which the extension at each end of said slot tapers towards its end.
- 25 5. A faller according to claim 1 in which said central portion of said body is integral with said head portions.
- 30 6. A faller for a textile machine, said faller comprising a body having a central portion of substantially uniform depth terminating at each end in a head portion of greater depth, said body being formed with a longitudinal slot passing through the depth of said body and defining spaced side members, at least one of said side members being thicker over the region of its mid-height, a mounting of rubber-like elastomer secured in said slot and a plurality of pins extending through and supported by said mounting.
- 35 7. A faller according to claim 6, in which each said side member has a longitudinal stiffening rib along its inner side formed by the thicker mid-height portion.
